UNITED STATES PATENT OFFICE.

LELAND S. ROSENER, OF SAN FRANCISCO, CALIFORNIA.

APPARATUS FOR UNLOADING BARGES.

Application filed October 16, 1919. Serial No. 331,085.

To all whom it may concern:

Be it known that I, LELAND S. ROSENER, a citizen of the United States, and a resident of the city and county of San Francisco, 5 State of California, have invented new and useful Improvements in Apparatus for Unloading Barges, of which the following is a specification.

My invention relates more particularly to 10 the unloading of barges carrying coal, or the like; and its primary object is to facilitate the transfer of the barge load to ships, or bunkers, with greater rapidity and more efficiently than heretofore.

15 This I accomplish by a combination of handling and transferring mechanism. My invention is particularly adapted to the coaling of ships.

By referring to the accompanying drawings 20 my invention will be made clear.

Fig. 1 is a part side view of a barge partly in section, equipped with my unloading apparatus.

Fig. 2 is a cross section of Fig. 1 on the 25 section line II—II, with certain of the parts shown in full for better illustration.

Fig. 3 is a diagrammatic cross section on the line III—III of Fig. 1, indicating the relative position of the bucket and load and 30 barge walls.

Fig. 4 is a diagrammatic showing of the way my apparatus will automatically unload to correct any "listing" of the barge.

Figs. 5 and 6 are details of the discharge 35 hopper to facilitate distribution of material from the barge to several points without moving the barge.

Fig. 7 is a detail of the skip and weighing platform.

40 Fig. 8 is a view of Fig. 7 and at right angles thereto.

Throughout the drawings like numerals refer to similar parts.

The hull of the barge is indicated by the 45 numeral 1, upon which is erected a gallows frame 2, within which is constructed the elevator mechanism adapted to operate and direct the skip 3. Above the barge 1, and supported by the frame structure 30, and parallel with the barge length, is mounted the track structure 29 and trolley 50, adapted to support the traveling grab bucket 5 from tracks 4; bucket 5 is adapted to pass through the gallows frame from end to end of the 55 barge 1, as shown in Fig. 2 and clears the maximum load 6, so that the grab bucket 5

may be caused to pick up its unit load from any portion of the barge load 6, and be lifted into a position clear of the remaining barge load, and caused to travel freely upon the tracks 4 through the gallows frame 2.

Mounted adjacent to the frame 2, is the 60 hopper 7, positioned to receive the load released from the grab bucket 5, and convey the load dumped therefrom into the skip 3, when the latter is properly positioned as shown in Fig. 2. The skip 3 is adapted to travel upward in the gallows frame 2, and clear the hopper 7 in so doing, and to travel to any required position and dump into the 65 discharge hopper 8, from which the load is distributed as by gravity into the bunkers to an adjacent ship or wharf.

The mechanism for operating the grab 70 bucket is controlled from suitable power actuated drums through the trolley line 9, adapted to move the bucket upon the tracks 4, and the bucket operating line 10 is adapted to operate the closing mechanism of the 75 grab bucket. These ropes pass over suitable sheaves in well known ways.

The several drums for the bucket operation are shown at 11, 12, 13. The skip is intended to be operated in a well known way by the wire rope 14 from the power actuated 80 drum 15 over suitable sheaves and pulleys, so that its raising and lowering is under accurate control.

To adapt the position of dumping to any 85 location of bunker to be loaded, I arrange a discharge hopper 8 adapted to travel in ways 16, supported with rollers 21, and to any suitable vertical position under the control of the wire rope 14 from the power actuated drum 18, so that it may be set at required 90 vertical positions at any time, and the load from the skip dumped therein. This dumping is effected automatically by the skip 3 having located on its side, track-ways as 19, 20, which are adapted to slide over the roller 95 or pins 21 of the discharge hopper 8, so that when the said pin 21 is in engagement between the tracks 19, 20, of the skip 3, any further vertical advance of the said skip will cause the skip to tilt so that its contents 100 will be discharged into the hopper 8. This dumping position is indicated in the dotted position 22; discharging the load by gravity 105 into the discharge hopper 8.

At 23 I provide a weighing platform suspended from the scales 24, and on which 110 platform the skip 3 may normally rest, be-

ing in such position free from the hoisting cable and frame, so that the accurate weight of the load placed in the skip 3 may be weighed upon the scales 24.

5 The means which I prefer to use for freeing the skip 3 from the hoisting mechanism is best shown in Figures 7, 8, wherein the U frame 25 is provided with long slots 26 on each side, within which slots the sup-
10 porting and turning axis of the skip 3, as indicated by pivots as at 27, may freely travel. Under the operation of the hoisting rope 14 the frame 25 may be raised when the bottom of the slots 26 will engage the
15 axle pins 27 of the skip 3 and raise the skip therewith.

Upon the unwinding of the rope 14 the skip 3 will descend until it rests upon the scale platform 23, and the U frame 25 will
20 further descend thus freeing the axle pins 27 and therefore the skip from all contact with the hoisting mechanism, the U frame 25 at such times resting upon the floor as at 28, free of the scale platform.

25 In some cases, as in coaling ships, it is advisable to distribute the coal through several different ports into the different bunkers of the ship, and the placing of the coal in any one of the said bunkers by the trim-
30 mmer gangs does not proceed with the rapidity with which the barge may be un-
loaded by my apparatus, and in such cases the discharge hopper 8 may be preferably arranged with a plurality of discharge out-
35 lets under the control of a movable gate, or gates, or diaphragm device, which may be actuated as by cable from below, such that any skip load may be distributed through the discharge hopper into any one of a plu-
40 rality of chutes, so that more than one gang of bunker trimmers may be kept employed by the rate of unloading accomplished with my apparatus. Such a distributing hopper is shown in Figures 5 and 6, wherein the
45 rolls, or pins 21, engage the uprising skip to tip it into the position 22 so that it dumps upon the bottom of the hopper 36. From here it will slide by gravity over the movable door 37 and through the outlet spout
50 38 into a suitable chute, or if the door 37 be raised against the jamb 39 as by the lever 40, the load will fall into the laterally distributing chutes 41, 42. These chutes 41,
55 42 are under the control of doors, or in the preferred construction shown, a wing gate 43 externally controlled by the lever 44, which in the position shown closes the chute 41 and rests against stop 47, and in which position it diverts material descending on
60 the bottom 36 through the opening occasioned by raising 37 against the jamb 39, which falling against the door 43, is diverted into the chute 42. The door 43 is actuated through the external lever 44, by
65 which it may be swung from the position

shown into the dotted position 45 against the support 46, at which time descending material will be diverted away from the chute 42 and through the chute 41.

70 In forming the bunker space in the barge I employ sloping sides as 31, 32, and the flat bottom 33, such that the grab bucket in descending vertically will in its open position fully cover the floor with 33, as indicated in Fig. 3.

75 With my apparatus it will be seen that in the event of any unequal lateral distribution of the load 6, causing "listing" of the barge, as indicated at 34 (Fig. 4) the grab bucket will, under the action of gravity, automatically swing into a position to take the load at the heaviest part, and thus act, at all times, to correct any listing; resulting in the maintenance of perfect trim or equilibrium of the unloading barge.

80 The operation is as follows:

85 My barge being loaded, as for example, with coal is brought alongside a ship that is to be coaled, and a suitable chute, or chutes, is placed between the discharge hopper 8, as indicated at 48 (Fig. 2), and the ship's bunkers, or bunker ports, the elevation of the discharge hopper 8 is set through the action of the drum 18 and cable 14, so that the coal will distribute by gravity from the 90 hopper 8 into the ship's bunkers through the chute 48; the grab bucket 5 is now caused to descend by the cable line or lines 35, and a load picked up, the bucket being closed by the action of the cable 10. The 95 loaded bucket is now raised and then transferred along the tracks 4 by the trolley line 9. The several cable lines 35, 10 and 9, being respectively operated by power drums, as required, as 11, 12, 13, until the bucket 100 5 occupies a position over the hopper 7, at which time, the line 10 is released by the operator at the drum 12, and the load dumped, when, under the action of gravity 105 a flow will occur into the skip 3, which has been previously set into the position shown in Fig. 2. The skip and its load are now weighed on the scale platform 23 by the scale beams 24, and the skip 3 is thereafter raised by the cable 14, through ways 110 17 and U frame 25 engaging axle pins 27; through the action of the power drum 15, until the tracks 19, 20, of the skip 3, in its upward passage engage between them the 115 pins, or rollers, 21, located on the discharge 120 hopper mechanism 8, causing the skip to tilt over, pivoting at such time on the axle pivots 27 within the frame 25. The skip in tilting to the dotted position as 22 will transfer its load by gravity into the discharge hopper, and thence into the ship through any one of the several chutes and to any of the several positions desired, depending upon the position of the control 125 gates 37 and 43 which determine its passage 130

through any one of the several outlets of the distributing hopper 8.

I prefer to make the capacity of the skip 3 slightly larger than the capacity of the bucket 5, so as to avoid the necessity for any storage in the hopper 7. The cycle of movement of the skip 3 is ordinarily shorter than the cycle of movement of the grab bucket 5, thus obviating the necessity for storage 10 within the hopper 7, and the attending costs and inconvenience of control gates and their operation for the said hopper.

In the longitudinal operation of the bucket 5, it is preferable to direct the successive trips of the bucket 5 so as to equalize the rate of longitudinal unloading. This rate will be entirely automatic, the grab bucket at all times will swing laterally to that portion of the cross section carrying 20 the greatest load and thus at all times correcting any "list."

Attention is directed to my Patent #1,370,226, issued March 1, 1921, wherein is set forth further disclosure and claims for 25 improvements in barges.

I claim:

1. A barge in combination with a bucket and hoisting and conveying means for said bucket, a hopper adapted to receive a load 30 from said bucket and discharge said load into a skip; a skip and a frame within which said skip is adapted to travel vertically; a discharge hopper adjacent to the path of the said skip into which a load from 35 the skip may be dumped, and power means for operating the bucket, and power means for operating the skip, said skip and frame being located at substantially the longitudinal center of the barge, said barge constructed with bunker walls sloping towards a flat bottom said bottom having a width substantially equal to the range of bucket sweep.

2. A barge in combination with a bucket 45 and hoisting and conveying means for said bucket, a hopper adapted to receive a load from said bucket and discharge said load into a skip; a skip and a frame within which said skip is adapted to travel vertically; a discharge hopper adjacent to the path of the 50 said skip into which a load from the skip may be dumped, and power means for operating the bucket and power means for operating the skip, said skip and frame being 55 located at substantially the longitudinal center of the barge, located centrally with respect to the barge load and vertically therefrom, said barge constructed with bunker walls sloping towards a flat bottom, said 60 bottom having a width substantially equal to the range of bucket sweep.

3. In a barge for coaling ships, longitudinal sides sloping towards a flat bottom; a transfer frame and tracks supported substantially central over the said bottom; a

grab bucket and means by which said bucket may be caused to take in or discharge a load, and means by which it may be raised or lowered, and means by which it may be transferred on said tracks; a skip constructed 70 and adapted to receive load discharged from said bucket and to elevate the said load thereafter to any required height; a traveling frame for said skip and means for operating the skip therein, and means to discharge the load from said skip. 75

4. In a barge for coaling ships, longitudinal sides sloping towards a flat bottom, a transfer frame and tracks supported substantially central over the said bottom; a grab bucket and means by which said bucket may be caused to take in or discharge a load, and means by which it may be raised or lowered, and means by which it may be transferred on said tracks; a skip constructed and 80 adapted to receive a load discharged from said bucket and to elevate the said load thereafter to any required height; a traveling frame for said skip and means for operating the skip therein, and means to discharge the 85 load from said skip, and weighing means on which the skip is adapted to rest in its lowest position and disengaging means by which the skip is disengaged from its associated mechanism when weighing. 90

5. In a barge for coaling ships, longitudinal sides sloping towards a flat bottom, a transfer frame and tracks supported substantially central over the said bottom; a grab bucket and means by which said bucket may be caused to take in or discharge a load, and means by which it may be raised or lowered, and means by which it may be transferred on said tracks; a skip constructed and 100 adapted to receive a load discharged from said bucket and to elevate the said load thereafter to any required height; a traveling frame for said skip and means for operating the skip therein, and means to discharge the 105 load from said skip, and disengaging means 110 and weighing mechanism consisting of a platform hung from a scale beam whereby the skip and its load may be weighed free of other parts.

6. In a barge for coaling ships, longitudinal sides sloping towards a flat bottom, a transfer frame and tracks supported substantially central over the said bottom; a grab bucket and means by which said bucket may be caused to take in or discharge a load, and means by which it may be raised or lowered, and means by which it may be transferred on said tracks, a skip constructed and adapted to receive a load discharged from said bucket and to elevate the said 120 load thereafter to any required height; a traveling frame for said skip and means for operating the skip therein, and means to discharge the load from said skip, and automatic disengaging means and weighing 125 130

mechanism consisting of a platform hung from a scale beam whereby the skip and its load may be weighed free of other parts.

7. In a barge for coaling ships, longitudinal sides sloping towards a flat bottom, a transfer frame and tracks supported substantially central over the said bottom; a grab bucket and means by which said bucket may be caused to take in or discharge a load, and means by which it may be raised or lowered, and means by which it may be transferred on said tracks; a skip constructed and adapted to receive a load discharged from said bucket and to elevate the said load thereafter to any required height, a traveling frame for said skip and means for operating the skip therein, and means to discharge the load from the skip, and weighing means by which the skip is disengaged from its associated mechanism when weighing; a discharge hopper to receive load from the skip, said hopper being vertically adjustable and co-operating means between said hopper and said traveling skip whereby the skip is caused to discharge its load into said hopper.

8. A coaling barge provided with a longitudinally extending bridge having a track thereon, a trolley mounted for longitudinal movement on said track, a grab bucket carried by said trolley, a tower located at an intermediate portion of the bridge, a skip or hoist bucket mounted for vertical travel in said tower, means for delivering the material from the grab bucket to the skip or hoisting bucket, and means for dumping the skip or hoisting bucket when elevated, substantially as described.

9. A coaling barge provided with a longitudinally extending bridge having a track thereon, a trolley mounted for longitudinal movement on said track, a grab bucket carried by said trolley, a tower located at an intermediate portion of the bridge, a skip or hoist bucket mounted for vertical travel in said tower, means for delivering material from the grab bucket to the skip or hoist bucket, and means for dumping the skip or hoist bucket when elevated, together with means whereby the bucket may be caused to

dump at different heights, substantially as described.

10. The combination of a barge provided with a longitudinal extending structure or bridge having a track thereon, a trolley arranged for longitudinal travel on said track, a grab bucket carried by said trolley, a tower located at an intermediate point of said barge and on one side thereof between said bridge and the side of said barge; a skip or hoist bucket mounted on suitable tracks for vertical travel in said tower, a chute for delivering by gravity the material discharged by the grab bucket to the skip or hoisting bucket when in its lowered position, means for elevating said skip or hoist bucket, and means for dumping same, and a movable or adjustable hopper and chute combined in which the bucket is dumped, said combined hopper or chute being also mounted in said tower or tracks for vertical movement, substantially as described.

11. A barge having a bridge extending longitudinally thereof, conveying mechanism arranged to travel on said bridge, a stationary tower located at an intermediate portion of the barge and to the base of which material may be delivered from both end portions of the barge, a hoisting bucket on said tower, and means for dumping said bucket when raised, substantially as described.

12. A coaling barge provided with a longitudinally extending bridge, a track on said bridge, a trolley mounted for longitudinal movement on said track, a grab bucket carried by the trolley, a tower located at an intermediate portion of the bridge, a skip mounted for vertical travel in said tower, means for delivering the material from the grab bucket to the skip, means for dumping the skip when elevated, and weighing means whereby each load of material is weighed before its discharge into said skip.

In testimony whereof, I have hereunto set my hand at the city of San Francisco, California, this 9th day of October, 1919.

LELAND S. ROSENER.
